Primary Examiner — Lauren R Calve(74) *Attorney, Agent, or Firm* — Boisbrun Hofman, PLLC(57) **CLAIM**

The ornamental design for a hanger apparatus, as shown and described.

DESCRIPTION

FIG. 1 is a front perspective view of a hanger apparatus, as assembled, showing our design;

FIG. 2 is a front perspective view of the hanger apparatus, with an exploded view showing the hook (top) portion and the body (lower) portion;

FIG. 3 is a front view of the hanger apparatus, as assembled;

FIG. 4 is a back view of the hanger apparatus, as assembled;

FIG. 5 is a left side view of the hanger apparatus, as assembled;

FIG. 6 is a right side view of the hanger apparatus, as assembled;

FIG. 7 is a top view of the hanger apparatus, as assembled; and,

FIG. 8 is a bottom view of the hanger apparatus, as assembled.

The dashed lines shown represent unclaimed subject matter only and form no part of the claimed design.

1 Claim, 3 Drawing Sheets(56)
